Specification of Letters Patent.

Patented Oct. 18, 1921.

Application filed June 14, 1917. Serial No. 174,686.

To all whom it may concern:

Be it known that we, JOHN L. LAKE, a subject of the King of Great Britain and a citizen of the Dominion of Canada, and 5 FRANCIS D. McMAHON, a citizen of the United States, both residing at Cleveland, in the county of Cuyahoga and State of Ohio, have invented a certain new and useful Improvement in Tractors, of which the following is a full, clear, and exact description, reference being had to the accompanying drawings.

This invention relates to improvements in tractors, particularly of the line drive variety and of the type having two large traction wheels from which is suspended practically the entire weight of the driving motor, mechanism and frame, thereby to enhance the traction.

20 The general objects are the attainment of simplicity and accuracy in the control of tractors of the above class, while maintaining the maximum of efficiency.

More specifically, the invention has for 25 its objects the provision of means, simple of construction and sure of operation for driving a tractor of the character aforesaid in reverse directions, at variable speeds, and for turning the tractor; and the accomplishment 30 of these ends by the use of two main lines and two auxiliary lines; the provision of cams shiftable by the use of lines in one direction and by tension means, as springs, in the opposite direction, for actuating 35 clutches in the attainment of the immediately foregoing results; and the inclusion of novel means for maintaining the clutch actuating cams in various shifted positions.

In tractors of the class above referred to, 40 the traction wheels carry large gears arranged concentric to the wheels and with which driving pinions mesh, while the main structure is spring suspended from the axle of the wheels. A further object of this invention is the provision of a construction 45 enabling the frame to swing with respect to the axle of the wheels on an arc described from the center of the driving pinions, wherefore a proper meshing of the pinions and gears is constantly maintained.

The foregoing, and other objects which will become apparent as this description proceeds, are attained in the construction illustrated in the drawings accompanying and 55 forming a part hereof, and wherein similar

reference characters designate corresponding parts throughout the several views.

In the drawings, Figure 1 is a plan view of the tractor; Fig. 2 is a central longitudinal section through the tractor (the engine, radiator, etc., being shown in elevation); Fig. 3 is a fragmentary transverse section through the tractor on the line 3—3 of Fig. 2, the plane of the section being indicated by the correspondingly numbered line of Fig. 4; Fig. 4 is a horizontal section through the transmission gear casing and the fly wheel of the engine, the section being taken on the lines 4—4 of Figs. 2 and 3; Fig. 5 is a vertical section on the lines 5—5 of Figs. 1 and 3; Fig. 6 is a transverse section through the change-of-speed gearing, the same being taken on the lines 6—6 of Figs. 1 and 4; Fig. 7 is a sectional detail on the line 7—7 of Fig. 6; Figs. 8 and 9 are sectional details on lines 8—8 and 9—9, respectively, of Fig. 1; Fig. 10 is a perspective view of the parts shown in Fig. 9 in separated condition; Fig. 11 is a perspective view of mechanism for shifting the 80 clutch-pinions through which forward and reverse drives of the traction wheels are obtained; and Fig. 12 is a similar view of one of the friction clutch actuating cams.

The traction wheels which are designated 85 1 are loosely mounted upon the ends of an axle 2 from which the frame is suspended.

The frame is made up of an upper section 4 and a lower section 5 that are connected and spaced apart by lacing members 6. It 90

will be seen, particularly from Fig. 1, that the opposite sides of the lower frame section 5 are spaced a like distance apart throughout their lengths, while the sides of the upper frame section are bent outward 95 just forward of their longitudinal centers and extend rearwardly across the axle 2 just inside the traction wheels. The frame 4 is made of outwardly opening channels, and secured to it, preferably by rivets 7, just above the axle are spring buttresses 8 from which depend guides 9 that are spaced apart and are curved on arcs described from the center of the driving shafts presently to be described. A bearing block 10 is 100 mounted for reciprocation between the guides 9 of each buttress and within the blocks 10 is journaled the axle 2. A spring support 12 is applied to the axle outside of each block 10, the support being split for application 105 110

to the shaft and adapted to be clamped firmly thereto by bolts 13 which pass through apertures in opposed ears 14 of the support. Each support is provided with spring seats 5 between which and the overhanging portions of the buttresses 8 are adapted to be confined springs 15. A plate 16 is secured to the lower ends of the guides 9 by screws 17 to prevent the withdrawal of the blocks 10.

10 A radiator 20 is supported by the forward end of the frame, and an internal combustion engine 21 of any approved type, is carried by the lower frame section 5 immediately to the rear of the radiator. It is customary to 15 employ a governor for controlling the engine speed in tractors of this sort, and this practice may be followed in the present instance. As shown in Fig. 4, the engine shaft 22 is equipped with a fly wheel 23 and has 20 connection, through an Oldham coupling 24, with the forward end of the driving shaft 26.

The transmission gear case 28 is supported, to the rear of the engine, by the lower frame section 5, and formed integral with this 25 case is a worm casing 29 and the lower half of the worm wheel casing 30. The driving shaft extends through the front removable wall 31 of the gear case, in alignment with the worm shaft 32 that is supported within 30 the worm casing 29, the shafts being journaled within suitable bearings 33 where they pass through the walls of the casing, the extreme rear end of the worm shaft being equipped with a thrust bearing 34 that is 35 backed up by a plate 35, secured to the rear recessed end of the casing by screws 36. The rear end of the driving shaft is piloted within the forward end of the worm shaft, as indicated at 38, and adjacent its rear end, 40 the driving shaft is squared at 39. A double faced clutch member 40 is slidably upon the squared portion 39, and is adapted to be shifted forwardly into coöperation with the clutch face 41 of a gear 42, loosely mounted 45 upon the driving shaft or rearwardly into coöperation with the clutch face 43 of a gear 44 that is secured by the key 45 to the forward end of the worm shaft. A shaft 46 has its ends supported in the front and 50 rear walls of the gear case 28, and loosely mounted upon this shaft is a hub 48 common to two gears 49 and 50, the former meshing with gear 42, and the latter with gear 44. A gear 52 is keyed to the driving shaft forward 55 of the gear 42 and meshes with a gear 53 that is loosely mounted upon a shaft 54 supported with its ends in the front and rear walls of the gear case. The rear end of the elongated hub 55 of the gear 53 is 60 squared, and a clutch member 56 is slidably mounted upon this squared portion of the hub for coöperation with a clutch face 57 of a gear 58 that is loosely mounted upon the shaft 54 and meshes with the gear 44.

65 It may be explained at this time that when the clutch member 40, is shifted forwardly it locks the gear 42 to the driving shaft, and this gear, through the gears 49 and 50 will drive the gear 44, and consequently the worm shaft, at a reduced speed 70 with respect to the driving shaft. The speed of the driving shaft may be transmitted to the rear shaft by shifting the clutch member 40 rearwardly into engagement with the clutch face 43 of the gear 44. To drive the 75 worm shaft at an increased speed over that of the driving shaft, the clutch member 56 may be shifted into coöperation with the clutch face 57 of the gear 58, for it will be observed that the gear 52 is keyed to the 80 driving shaft and is, therefore, constantly rotating with it, and its motion is transmitted through the gear 53, clutch member 56 and gear 58, to the gear 44 of the worm shaft, the ratio of the gears being such as to 85 cause an increase over the speed obtained through the gear combinations previously described. Clutch members 40 and 56 are shifted by mechanism which will now be described.

90 Referring particularly to Figs. 6 and 7, 60 is a plate that is slidably mounted within guides 61 in the top portion of the gear case 28. Just below the plane of the plate, rods 62 and 63 are slidably supported within 95 the front and rear walls of the gear case, and the former has clamped to it a fork 65 which embraces the clutch member 40, while the latter has secured to it a fork 66 which embraces the clutch member 56. Clamped 100 to the respective rods 62 and 63 are arms 68 and 69, the former carrying an anti-friction roller which is arranged to traverse a cam slot 70 and the latter a friction roller arranged to traverse a cam slot 71, in the 105 plate 60.

110 In the position shown in Fig. 7, the clutch members are in neutral position and the rollers of the arms 68 and 69 occupy what shall be termed neutral portions of the slots 110 70 and 71, the neutral portions of the slots being shown as substantially coincident with the longitudinal axis of the plate. When the plate 60 is moved to the right, it will be seen that a portion of the slot 70 115 which is inclined forwardly from its neutral portion will embrace the roller of the arm 68 and through said arm shift the rod 62, with the fork 65 and clutch member 40, forwardly to obtain what I have already referred to as low speed. During this movement of the plate, the clutch member 56 will remain idle for there is no divergence from the neutral zone of the slot 71. The plate may be shifted a given distance to the left 120 without affecting the clutch member 56, but upon such movement of the plate, the fork 65 will be shifted rearwardly because of the rearward inclination of the slot 70 just to the right of its formerly mentioned neutral 125 zone.

130

portion, and in so shifting the fork 65 and the clutch member 40, what may be termed "second speed" is obtained, as above explained. Upon a further movement of the 5 plate to the left, the adjacent forwardly inclined portion of the slot 70 returns the fork 65 and clutch 40 to neutral position, while a rearward extension of the slot 71 causes the fork 66 and clutch member 56 to 10 be shifted rearwardly in the attainment of high speed. The plate 60 is moved to the left by a spring 73 which has one of its ends anchored at 74 to the gear case, while its opposite end is secured at 75 to the plate. 15 The plate is adapted to be shifted against the action of this spring by a line 76 which is secured to one branch of a bell crank lever 77 that is pivoted at 78 to the plate 60. The opposite end of the bell crank lever 20 has a nose 79 that is adapted to be projected into notches 80 in the side of the adjacent guide 61, by a spring 82 which, it may be said, is considerably weaker than the spring 73. Each of the notches 80 represents one 25 effective position of the plate 60. When the line 76 is pulled, it first withdraws the nose 79 of the bell crank lever from a notch 80, and a further pull upon the line will shift the plate to the right. By relaxing the line 30 rather gradually the bell crank lever may be held with its nose withdrawn beyond the plane of the notched guide 61, which will enable the plate to be shifted its full movement to the left by the spring 73 if such is desired. On the other hand, should it be desired to arrest the movement of the plate at any one of the notches 80, the plate may be 35 shifted so that the nose of the bell crank is to the right of the desired notch, and then, 40 by quickly releasing the line, the nose will be thrown against the edge of the guide 61 and will be projected into the notch by the spring 82 instantly upon its reaching the same.

45 A worm 85, upon the worm shaft 32, meshes with a worm wheel 86 that is housed within the casing 30 and is keyed to the shaft 87 which extends transversely of the machine and is journaled within bearings 50 88 that are mounted within the sides of the casing 30. The ends of the shaft 87 project just outside the casing where they have keyed to them the external members of friction clutches 90. The internal member 91 55 of each of the friction clutches is splined to a short shaft 92 which has its inner end piloted within the adjacent end of the shaft 87, as shown at 93, and its outer end journaled within the upper end of a bracket 94 which rises from the frame section 5. Each 60 shaft 92 has a pinion 95 just inside the bracket 94 and a spring 96 is interposed between the pinion and the clutch member 91 to normally hold the clutch members in frictional engagement.

On each side of the machine and in the vertical plane of the shafts 92, is supported a hollow shaft 100 within bearings 101 and 70 102. The latter bearing is suspended from a cross-brace 103 on the upper frame section 4, while the former is contained within a housing 104 that is suspended from the frame section 4 at the junction of the cross brace 103. A pinion 105 is keyed to the shaft 100 and meshes with the pinion 95 of the adjacent shaft 92. Slidably mounted upon the extreme outer end of each shaft 100 is what may be termed a clutch-pinion 75 108, the same being splined to the shaft through the feather 109. The teeth of the pinion are represented at 110 and the pinion carries on its inner side a clutch face 111 for coöperation with the clutch face 112 of what I shall term a "bull pinion" 113. This pinion is made up of a hub portion 114, 80 which is rotatably mounted upon the shaft 100, and from which extend circumferential longitudinally spaced flanges 115 between which are mounted anti-friction rollers 116, the inner flange being shown as cored to provide a lubricant chamber 117 that is adapted to be supplied with oil through an oil cup 118. The bull pinion constantly meshes with a "bull gear" 120 supported from the rim of the adjacent traction wheel 1 by 85 brackets 121, the "bull gear" being an internal gear as clearly shown in Fig. 2. When either of the clutch-pinions 108 is in its extreme outer position its teeth 110 mesh with an external gear 125 which is carried 90 by extensions 126 of the brackets 121, the gears 125 being referred to hereinafter, because of their function, as the reversing gears. The clutch-pinions 108 have a neutral position when they neither coöperate 95 with the reversing gears 125 nor the clutch faces of the "bull pinions." A cylindrical casing 128 is carried by the "bull pinions" and incloses the clutch-pinions except when the latter are in mesh with the reversing 100 gears.

A rod 130 extends through the bore of each shaft 100, and near its outer end has a transverse groove 131 which receives the inner end of a finger 132 that is secured to the clutch-pinion 108 and projects through a slot 133 in the shaft. The bore of the shaft is enlarged at its inner end to receive a rider 135 which is swiveled to the adjacent end of the rod 130, and between a thrust bearing 136, which bears against the inclosed end of the rider, and the opposed annular wall of the enlargement of the bore, there is interposed a spring 138 which tends to move the rod inwardly and carry the clutch-pinion 115 into coöperation with the clutch face of the "bull pinion" 114.

Supported by hangers 140, from the cross-brace 103, just inside the inner ends of shaft 100, is a pair of plates 141 between which is 120 125 130

guided a cam 142, the cam face whereof is arranged for coöperation with a roller 143, carried by the rider 135. This cam, with its supporting structure, is shown in detail 5 in Fig. 11. The cam is adapted to be stopped in three positions by a pawl 145 which is pivoted between two ears 146 rising from the upper plate 141, the nose of the pawl playing within a slot 147 in the top 10 plate and adapted to enter any one of three recesses 148 in the cam. The cam has three face portions 142^a, 142^b, and 142^c, the portion 142^b constituting what may be termed the neutral face of the cam, for, when the 15 roller 143 is in engagement with this face the rod 130 is positioned to maintain the clutch-pinion 108 out of engagement with the reversing gear 125, and free from the clutch face 112 of the "bull pinion." A line 20 150 is attached to the rear end of each cam 142, and by this line the cam may be drawn rearwardly against the tension of a spring 151 (Fig. 5) interposed between a depending lug 152 of the cam and a projection 153 25 of the lower plate 141, the projection being apertured for the free passage of a rod 154 which has its forward end secured in the lug 152 and which serves to maintain the aforesaid spring in place. By a jerk upon 30 the line 150 the pawl 145 may be rocked on its pivot to withdraw its nose from the intermediate recess, the pawl being rocked by engagement with the forward wall of the recess. The pawl is so nearly balanced 35 that before it has time to resume effective position, the line may be released sufficiently to allow the spring 151 to move the cam forwardly so that the face 142^c is brought into engagement with the roller 143 allowing the 40 clutch-pinion to engage the clutch face of the "bull pinion" and thus lock the "bull pinion" to the shaft 100. By drawing the cam to the extreme limit of its backward movement, where it is held by the pawl 145 45 engaging the forward recess 148, the face 142^a is brought into engagement with the roller 143 whereupon the rod 130 will be projected outwardly to carry the clutch-pinion into mesh with the reversing gear 50 125.

Remembering that the foregoing mechanism is duplicated with respect to both traction wheels it will be seen that, by means of lines 150, the tractor may be driven forward, stopped, reversed, or by retaining 55 one clutch-pinion in neutral position while engaging the other with the "bull pinion" or reversing gear, the tractor may be turned; or again by allowing one of the clutch-pinions 60 to mesh with the reversing gear and the other to coöperate with the "bull pinion," the tractor may be spun around practically in its own tracks. However, there are situations which require a nicer and more accurate control than that afforded by the mere 65

shifting of the clutch-pinions, and for this reason the friction clutches 90 are employed. By means of these clutches the drive through either traction wheel may be rendered more or less positive or null as desired. These 70 clutches provide what may be regarded as a manually controlled differential movement between the traction wheels. They are actuated by a mechanism which will now be described.

The branches of a fork 158 are connected to the shifting collar 159 of each clutch member 91, and the fork is fulcrumed upon a vertical pin that is supported in the outer ends of arms 160 extending from the adjacent side 80 of the wormwheel casing 30. A roller that is carried by the shank of each fork reposes within the groove of a segmental cam 161, clamped or otherwise secured to a rock shaft 162, journaled within bearings 163. As 85 shown in Figs. 1 and 12, the groove of each cam has a straight portion through which the roller of the shifting fork may play with no effect; but the lower end of the groove of the right hand cam (looking forward in Fig. 90 1) is inclined inwardly so that upon rocking the cam upward the rear end of the fork will be swung inwardly to move its opposite end with the clutch member 91, outwardly against the tension of the spring 96, thereby 95 to disengage the member 91 from the driving member of the clutch. In the case of the left hand cam, the upper end of its groove is inclined inwardly so that by rocking this cam downwardly the same result as that described in connection with the right hand clutch is now obtained in the left hand clutch. A comparatively strong spring 164 is coiled about the left hand end of the shaft 162 and has one of its ends attached to the 100 shaft and the other attached to a sector 165 which, as shown most clearly in Fig. 8, is carried by a plate 166 secured to and extending between the rear ends of the frame sections 4 and 5. A lever 168 is fastened to 110 the left hand end of the shaft 162 adjacent the sector 165 and its upper end has pivoted to it a bell crank 169, and a line 170 is secured to the free end of the vertical arm of the bell crank. The outer end of the other 115 arm of this bell crank has a nose 171 adapted to enter one of the three notches 172 of the sector, and a spring 173 tends to swing the bell crank in a direction to project its nose into the notches.

From the foregoing it will be seen that when the line 170 is pulled, the bell crank will be rocked to release the arm 168 from the sector, so that the shaft 162 may be rotated in one direction by the spring 164 and 125 in the opposite direction by the line 170. By drawing the arm rearwardly from its intermediate position the shaft 162 will be rocked in a direction to render the right hand clutch 90 ineffective, and when the shaft is permit- 130

ted to be rotated in the opposite direction by the spring 164, the left hand clutch is rendered ineffective. It is clear that the arm 168 may be stopped in any of its three positions by carrying it far enough beyond the position desired to allow the nose of the bell crank to swing into engagement with the periphery of the sector before it reaches the desired notch on its return movement, so 10 that as soon as it does reach such notch it will be projected thereinto by the spring 173, the line 170, of course, having been fully released. To assist the operator in determining the three positions of the arm, a plunger 15 175, set in a boss of the arm and spring pressed against the surface of the sector, is arranged to enter one of three depressions 176 in the sector, the location of the depressions corresponding to the three 20 positions. As the plunger passes the depressions it may readily felt by the operator.

The fork 184 of a caster 185 is journaled within a vertical boss 186 of a frame 187, 25 said frame comprising an upper and a lower branch each of which has its forward end bifurcated for the reception of a flange 188 of the respective upper and lower frame sections 4 and 5. A series of holes are formed 30 in each of the flanges 188 so that the frame 187 may be shifted laterally as desired to accommodate the draw bar of the drawn implement or vehicle. To prevent the frame 187 from swinging sidewise, a brace 35 rod 190 has its rear end attached to a lug 191 of the boss 186 and its forward end secured in any one of the holes in the horizontal flange of an angle bar 180 attached to the plate 166. A spring 192 is incorporated in 40 a well known manner in the connection between the caster fork and boss 186 to afford a yielding connection between the two so as to partially absorb the shocks of the road. When the implement or vehicle to be drawn 45 is of such nature as to maintain the rear end of the tractor frame at about normal elevation, the caster and frame 187 may be dispensed with and the draft mechanism of the implement or vehicle connected directly to the flanges 188. A seat 194 is carried, 50 through an arm 195, from the boss 186 in convenient position for the driver who may place his feet upon rests 196 which extend from the sides of the boss. The lines 150 55 may be led backward through apertures in the plate 166 within easy reach of the driver's seat. The line 76, which controls the cam plate 60 of the transmission gear, and the line 170, through which the cam 60 shaft 162 may be rocked for releasing the clutches 90, are herein shown as a continuous cable which may pass rearwardly through apertures in the plate 166 and around rollers 197 and through an eye 198 which rises from 65 the arm 195 immediately in front of the

driver's seat, so that the line may be in easy reach of the driver at all times.

As will be seen upon referring to Fig. 4, a beveled gear 200 is keyed to the rear end of the worm shaft 32, and meshes with a 70 similar gear 201 which has its hub journaled within a bearing 202 in the side of the worm-casing 29. A square socket is formed in the hub of the gear 201 and receives the correspondingly shaped extension 203 of a shaft 75 204 which is supported in a journal box 205 secured to the side of the frame section 5; and beyond this journal box the shaft has applied to it a belt pulley 206. Through this means, power may be derived from the 80 tractor for driving such apparatus as threshing machines, cement mixers, etc. The connection between the shaft 204 and gear 201 allows an easy removal of the shaft by simply loosening the collar 208. (normally located just inside the journal box) 85 and withdrawing the shaft endwise through its bearing. In cases where the pulley is not needed it may be desirable to remove it entirely. 90

An example of the liner for the bearing housings, eliminating the boring or machining of the housings to produce a finished interior for the reception of the bearings, hereinbefore set out as a feature of the invention, is 95 found associated with the bearings 88 and 101 in Fig. 3. In each instance, the liner is designated 210. In lining the housings, they are arranged with their open side uppermost and a mandrel, having the size and 100 shape of the bearing that is to occupy the housing, is supported in proper position within each housing, after which molten material, such as babbitt, is poured about the mandrel and allowed to harden, after 105 which the mandrel may be removed, leaving the interior of the housing smooth and completely finished ready to receive the bearing. Thus rough castings may be quickly prepared for use without the need of any tool 110 work whatever.

Having thus described our invention, what we claim is:—

1. In apparatus of the character set forth, the combination of a motor, a traction wheel, an internal and an external gear through which said wheel may be driven, a shaft, driving connections between the shaft and motor, a pinion loose on the shaft and in mesh with one of said gears, a second 115 pinion non-rotatable but slideable upon the shaft into and out of mesh with the other gear, said pinions having clutch faces arranged for engagement with each other, and mechanism for shifting the second pinion. 120 125

2. In apparatus of the character set forth, the combination of a motor, a traction wheel, an internal and an external gear through which said wheel may be driven, a shaft, driving connections between said shaft and 130

the motor, a pinion loose on said shaft and in mesh with one gear, a second pinion non-rotatable but slideable upon the shaft, said pinions having complementary clutch faces, 5 means tending to shift the second pinion with its clutch face in engagement with the clutch face of the first pinion, and means whereby said pinion may be shifted in opposition to the aforesaid means to an ineffective position or into mesh with its respective gear.

3. In apparatus of the character set forth, the combination of a motor, a pair of opposed traction wheels, a set of two gears 15 through which each wheel may be driven, a shaft associated with each set of gears, driving connections between the motor and said shafts, a pinion loose on each shaft and meshing with one of said gears, a pinion 20 slideable upon but non-rotatable with respect to each shaft, said pinions of each shaft having complementary clutch faces, the second pinion being shiftable into mesh with its respective gear, or with its clutch face in 25 engagement with the clutch face of the first pinion, or to an ineffective position, means tending to maintain each of the second pinions in one of said positions, and further means whereby said pinion may be shifted 30 to either of its other positions.

4. In apparatus of the character set forth, the combination of a motor, opposed traction wheels, a pair of gears through which each wheel may be driven, a shaft associated 35 with each pair of gears, driving connections between the motor and each shaft, a pinion loosely carried by each shaft and meshing with one of said gears, a second pinion slideable upon but non-rotatable with respect to 40 each shaft, the pinions of each shaft having complementary clutch faces, a reciprocable member through which each of the second mentioned pinions may be moved into mesh with its respective gear or with its clutch 45 face in coöperation with the clutch face of the first pinion or to an ineffective position, a cam for reciprocating the aforesaid member, and further means for moving the cam in reverse directions.

5. In apparatus of the character set forth, the combination of a motor, opposed traction wheels, a pair of gears through which each wheel may be driven, a shaft associated with each pair of gears, driving connections 55 between the motor and each shaft, a pinion loosely carried by each shaft and meshing with one of said gears, a second pinion slideable upon but non-rotatable with respect to each shaft, the pinions of each shaft having 60 complementary clutch faces, a reciprocable member through which each of the second mentioned pinions may be moved into mesh with its respective gear or with its clutch face in coöperation with the clutch face of the first pinion, a 65 cam for moving the rod in a reverse direction, means tending to move the cam in one direction, and means for moving said cam in the opposite direction.

a cam for moving each of the reciprocable members, means tending to move said cam in one direction, and further means for moving the cam in opposition to the first mentioned means.

6. In apparatus of the character set forth, the combination of a motor, opposed traction wheels, a pair of gears through which each wheel may be driven, a hollow shaft associated with each pair of gears, driving 75 connections between the motor and each shaft, a pinion loosely mounted upon each shaft and meshing with one gear, a second pinion slideable upon but non-rotatable with respect to each shaft and adapted to mesh 80 with the other gear, said pinions having complementary clutch faces, a rod reciprocable within said shaft, connections between the rod and second pinion, a cam for moving the rod thereby to shift the second pinion, means 85 tending to move the cam in one direction, and means through which the cam may be moved in opposition to the first means.

7. In apparatus of the character set forth, the combination of a motor, opposed traction wheels, a pair of gears through which each wheel may be driven, a hollow shaft associated with each pair of gears, driving 90 connections between the motor and each shaft, a pinion loosely mounted upon each shaft 95 and meshing with one gear, a second pinion slideable upon but non-rotatable with respect to each shaft and adapted to mesh with the other gear, said pinions having complementary clutch faces, a rod reciprocable within 100 said shaft, connections between the rod and second pinion, means impelling said rod in one direction, a cam for moving the rod in a reverse direction, and means for reciprocating the cam.

8. In apparatus of the character set forth, the combination of a motor, opposed traction wheels, a pair of gears through which each wheel may be driven, a hollow shaft associated with each pair of gears, driving 110 connections between the motor and each shaft, a pinion loosely mounted upon each shaft and meshing with one gear, a second pinion slideable upon but non-rotatable with respect to each shaft and adapted to mesh 115 with the other gear, said pinions having complementary clutch faces, a rod reciprocable within said shaft, connections between the rod and second pinion, means impelling said rod in the direction to shift the second 120 pinion with its clutch face in coöperation with the clutch face of the first pinion, a cam for moving the rod in a reverse direction, means tending to move the cam in one direction, and means for moving said cam 125 in the opposite direction.

9. In apparatus of the character set forth, the combination of a motor, opposed traction wheels, a shaft through which each wheel is driven, transmission gearing op- 130

- eratively connected to the motor, a clutch for each shaft and through which said shaft may be coupled with the transmission gearing, common means for controlling said 5 clutches movable in opposite directions to render the respective clutches ineffective, means tending to move the controlling means in one direction, and flexible means for moving said controlling means in the opposite 10 direction.
10. In apparatus of the character set forth, the combination of a motor, opposed traction wheels, a shaft through which each wheel is driven, operative connections between the motor and each shaft, said connections involving a clutch for each shaft, means tending to maintain each clutch in effective condition, controlling means movable in opposite directions to render the 15 respective clutches ineffective, means tending to move the controlling means in one direction, a device for moving the controlling means in the opposite direction, means acting automatically to retain said device in various positions, and further means for rendering said retaining means ineffective and for moving the device in opposition to the former moving means.
11. In apparatus of the character set forth, the combination of a motor, opposed traction wheels, a shaft through which each wheel is driven, operative connections between the motor and each shaft, said connections involving a clutch for each shaft, means tending to maintain each clutch in effective condition, controlling means movable in opposite directions to render the respective clutches ineffective, means tending to move the controlling means in one 20 direction, a device for moving the controlling means in the opposite direction, a graduated retaining member, a pawl movably carried by the device for coöperation with said retaining member, means tending to hold said pawl in effective condition, and further means for rendering said pawl ineffective and for moving the device in opposition to the aforesaid moving means.
12. In apparatus of the character set forth, the combination of a motor, opposed traction wheels, a driving shaft for each wheel, operative connections between the motor and shafts, said connections involving a clutch for each shaft, means tending 25 to maintain each clutch in effective condition, a rock shaft, cams upon said rock shaft one for disengaging one clutch when the shaft is rocked in one direction, and the other for disengaging the other clutch when the shaft is rocked in the opposite direction, a spring tending to rock the shaft in one 30 direction, an arm secured to said shaft, a pawl pivotally connected to the arm, a sector having pawl engaging notches, a spring tending to rock the pawl to engaging position, and means connected with the pawl for rocking it in opposition to the last mentioned spring and through which said arm may be rocked in opposition to the first 35 spring.
13. In apparatus of the character set forth, the combination of a motor, a traction wheel, a gear for driving said wheel in a forward direction, a second gear for driving the wheel in a reverse direction, a shaft, driving connections between the shaft and motor, a member shiftable upon said shaft for operatively connecting it with the first or second gear, a reciprocable element for shifting said member in opposite directions, a cam for reciprocating said element, means tending to move the cam in one direction, further means for moving the cam in opposition to the last mentioned means, a device for maintaining the cam in various positions against the action of the first mentioned means, said device being rendered temporarily ineffective upon the operation of the second mentioned cam moving means.
14. In power transmitting mechanism involving a driving member and a driven member, and means for effecting a driving connection between said members, a shiftable plate actuating said means, said plate having a plurality of apertures therein, a pivoted retaining device adapted to enter said apertures as said plate is shifted, said device being rendered temporarily ineffective by the movement of said plate in one direction, and means for moving said plate in reverse direction.
15. In power transmitting mechanism involving a driving member and a driven member, and means for effecting a driving connection between said members, a shiftable plate for actuating said means, means tending to move said plate in one direction, a retaining device pivotally supported in operative relation to said plate for coöperation therewith to hold said plate in various 90 positions against the action of the second mentioned means, and means for moving said plate in the opposite direction, the plate having portions for engaging and swinging said device temporarily from effective position when said plate is moved by the last mentioned means.
- In testimony whereof, we hereunto affix our signatures.

JOHN L. LAKE.
FRANCIS D. McMAHON.
